POWER UNIT

Ray F. Thornton, Dearborn, Mich.

Application October 6, 1944, Serial No. 557,511

4 Claims. (Cl. 74—16)

1

The present invention relates to a power unit and more particularly to a stationary power unit in which a plurality of separate internal combustion engines are interconnected for unitary operation to supply power to a single power take-off shaft.

Internal combustion engines, such for example as those used in automotive vehicles, have been highly developed and because of the mass production methods utilized in their manufacture are available at a relatively low cost per horse power output. In addition, standard replacement parts are readily available and a large number of trained automotive mechanics are available to perform the necessary service operations thereon.

Stationary power units to supply sufficient power in various installations may require more shaft horse power at times than can be developed by a single conventional automotive type of internal combustion engine. However, a plurality of such engines may, according to the present invention, be interconnected for unitary operation to supply the required shaft horse power to a single power take-off shaft. By utilizing a plurality of such engines, the power output may be readily varied to compensate for the load requirement, either by varying the number of separate internal combustion engines in operation, as by cutting in or cutting out certain of the engines, or by operating the connected engines at lower speeds. In either instance the power unit of the present invention provides a flexibility in operation which frequently is lacking in stationary power units in which a single heavy duty relatively large horse power internal combustion engine is utilized.

By way of example, but not of limitation, a stationary power unit of the present invention may be utilized to supply power to portable machinery of various types, such for example as portable saw mills, earth handling and moving equipment, stone and rock crushers and the like or similar equipment. It may also be used to drive pumping equipment and electricity generating equipment. In general, a power unit of the present invention may be utilized wherever a heavy duty stationary internal combustion engine is suitable for use as the power unit.

The principal objects of the present invention are:

1. To provide a power unit particularly adapted for use as a stationary power unit and in which a plurality of separate internal combustion en-

1 2

gines are interconnected for unitary operation to supply power to a single power take-off shaft.

2. To provide a stationary power plant of compact design in which the power is generated by a plurality of separate internal combustion engines which are interconnected for unitary operation, the engines being capable of separate operation when desired.

3. To provide a power unit in which power is generated by a plurality of separate interconnected internal combustion engines mounted in a unitary frame of unique and rigid construction.

10 4. To provide a power unit in which power generated by a plurality of separate interconnected internal combustion engines is delivered to a single power take-off shaft which is adjustably mounted for bodily movement relative to the frame of the power unit and relative to the drive shafts of the said internal combustion engines.

15 25 Other objects of the present invention will appear in the following description and appended claims, reference being had to the accompanying drawings forming a part of this specification wherein like reference characters designate corresponding parts in the several views.

In the drawings:

Fig. 1 is a perspective view of the power unit of the present invention with the side cover plates 30 removed to reveal the construction thereof.

Fig. 2 is a side elevation of a power unit embodying the present invention with the side cover plates in closed position.

Fig. 3 is a cross-section taken substantially on 35 the line 3—3 of Fig. 2 in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

40 45 A power unit of the present invention comprises a plurality of separate internal combustion engines 10, which are preferably of the automotive type and of any desired conventional construction. In the present drawings two such engines are shown by way of example, but it is to be understood that any desired number, more than two, may be utilized within the scope of the present invention. The conventional type en-

gines are each provided with a conventional type clutch which is connected to a unitary clutch control shaft 11, which is controlled by a clutch operating lever 12. The engines 10 each drive a stub-shaft 13 which is connected through a conventional type universal joint 14 with an arbor shaft 15 to which a drive pulley 16 is connected. Each arbor shaft 15 is journaled in fixed bearings 17 and 18 mounted respectively on cross-frame members 19 and 20 of the power unit frame.

Each engine 10 is provided with fuel from a separate fuel tank 21 through its conventional fuel feeding system. Each tank 21 is provided with a filling spout 22 which extends above the top of the unit and is closed by a removable filler spout cap 23.

Conventional types of indicating instruments, such for example as ammeters, tachometers and the like (not shown) are operatively connected with each engine 10 and are mounted on an instrument panel 24 provided in the dash 25, one instrument panel 24 being provided for each of the engines.

Each engine 10 is provided with a separate cooling system which comprises a conventional type of fluid radiator 26 having a filler spout 27 extending above the top plane of the unit and closed by a removable filler spout top 28. Air is drawn inwardly through the radiator core and blown over each engine 10 by a conventional type of automotive engine cooling fan 29.

The exhaust manifold of each engine 10 is connected with its own exhaust pipe 30 and exhaust gas muffler 31. While the muffler 31 may be of any desired construction, I prefer to use the muffler construction shown in my co-pending application Serial No. 525,525.

The engines 10 are synchronized for operation as a unit, preferably by balancing the intake manifold pressures, one suitable balancing mechanism being shown by way of example in my co-pending application Serial No. 524,402.

The governor controlled intake valve and the manually controlled carburetor intake valve are preferably connected by any suitable type of adjustable connecting and control device. However, it is to be understood that any other types of engine synchronizing and control mechanisms may be employed if desired.

The entire power unit is mounted in a frame which comprises a pair of base frame members 32 rigidly connected in spaced substantially parallel relation by a plurality of cross-frame members 33, and end frame members 34 and 35. The base frame members 32, cross-frame members 33 and end frame members 34 and 35 are all preferably channel shape in cross-section to impart greater strength and rigidity thereto.

The base members 32 are preferably each provided with a plurality of eyes 36 to permit connection of conventional types of hooks employed with hoisting or moving equipment. The ends 37 are shaped to permit use of the base members 32 as skids for moving the power unit into operating position as for example on a plurality of spaced base members 38, which, if desired, may be structural elements of the machine with which the power unit of the present invention is to be used.

A plurality of vertically extending corner frame members 39 are secured to the tops of the base frame members 32 and to the tops of the end frame members 34 and 35, and support a plurality of side sills 40 of the main frame. The side sills 40 of the main frame are secured in spaced substantially parallel relation by the cross-frame

members 19 and 20 and by a front cross-frame 41. A longitudinally extending frame 42 connects the front cross-frame 41 and the cross-frame 19. The longitudinally extending frames 42 extend substantially parallel to the side sills 40 and are spaced therefrom to permit the engines 10 to be suspended between them. The side mounting brackets of the engines 10 are secured to the longitudinal frame member 42 and to the side sills 40 by a plurality of any suitable type of vibration absorbing motor mountings 43. By this construction, the engines 10 are each resiliently suspended in a rigid cradling frame.

Secured to the tops of the side sills 40 and the main frame are a plurality of upright top frame members 44 to which is secured the top and top frame 45 from which the fuel tanks 21 are suspended.

A longitudinally extending flange 46 is provided on each side of the top and top frame 45 for receiving the top longitudinal edge portion of a removable side cover 47, the bottom edges of which are held in a plurality of longitudinally spaced cover brackets 48 secured to the side sills 40 of the main frame. A plurality of spring clips 49 are secured to the cover 47 to engage the longitudinal edge of the flange 46.

The single power take-off shaft 50 is provided with a connector flange 51 and is journaled in bearings 52 and 53 slidably mounted in vertically extending rigid bearing slides 54 and 55. The bearing slide 54 is connected to the cross-frame 20 of the main frame and to the end cross member 35 of the base frame. The bearing slide 55 is aligned with the bearing slide 54 and extends substantially parallel and in spaced relation thereto. It is secured to the cross-frame member 19 of the main frame and one of the plurality of cross-members 33 of the base frame.

A drive pulley 56 is secured to the power take-off shaft 50 between the bearings 52 and 53. The drive pulley 56 is driven from the engine driven drive pulleys 16 by a plurality of flexible V drive belts 57.

Vertical adjustment of the drive pulley 56 of the power take-off shaft 50 to take up slack in the drive belts 57 or to permit changes in the drive ratios by the substitution of a different size drive pulley 56, is provided by adjusted vertical movements of the bearings 52 and 53 in the bearing slides 54 and 55. The vertical adjustment of the bearings 52 and 53 is effected through bearing slide adjusting screws 58 and 59. The adjustment of the bearings 52 and 53 in the bearing slides 54 and 55 is maintained by lock nuts 60 and 61 on the bottom adjusting screws 59.

The various frame elements heretofore described are interconnected to form a single unitary frame construction which is rigid and has a high strength-weight ratio. The various parts of the frame may be secured in any suitable manner preferably by welding, but any other suitable means, such for example as bolts, rivets or the like, may be employed for this purpose.

The drive transfer mechanism herein disclosed may be replaced if desired by a drive gear mechanism in which event the transfer drive mechanism herein disclosed would be replaced by a gear case and gears therein.

From the foregoing it will be seen that I have provided a novel power unit construction in which a plurality of separate internal combustion engines are interconnected for unitary operation to supply power to a single power take-off shaft, and in which the separate engines are capable of

separate operation when desired, and are mounted in a unitary frame of unique and rigid construction. Power units embodying the present invention have been used successfully in various installations where a single heavy duty relatively large horse power internal combustion engine was previously employed as the power source. The greater flexibility and the greater economy in the repair or replacement of worn parts and the servicing of the units by readily available trained automotive mechanics and has been found to be particularly advantageous.

I claim:

1. A power unit including a plurality of separate internal combustion engines interconnected for unitary operation to supply power to a single power take-off shaft and having a rigid frame including a base frame and a vertically spaced motor supporting frame secured to said base frame, and including spaced substantially parallel side frames interconnected by a plurality of cross-frame members, a drive shaft connected with each engine and journaled in a pair of spaced vertically adjustable bearings, slidably mounted in a pair of spaced slide members secured between vertically spaced cross-frame members of said base frame and said motor supporting frame, means associated with said slide members for adjustably moving said bearings in said slide members, a power take-off shaft and means connecting said drive shafts in driving relation to said power take-off shaft.

2. A power unit including a plurality of separate internal combustion engines interconnected for unitary operation to supply power to a single power take-off shaft and having a rigid frame including a base frame having a pair of spaced substantially parallel longitudinally extending side skid members and a vertically spaced motor supporting frame secured to said base frame, and including spaced substantially parallel side frames interconnected by a plurality of cross-frame members, a drive shaft connected with each engine and journaled in bearings secured to a pair of said cross-frame members, a power take-off shaft, means connecting said power take-off shaft in driving relation to said power take-off shaft, a pair of vertically adjustable bearings, one adjacent each end of said power take-off shaft for rotatably journaling said power take-off shaft, and means for permitting vertical adjustment of

said bearings and comprising spaced slide members each extending between aligned vertically spaced cross-frame members, one on said base frame and one on said motor supporting frame, and adjustable means associated with said slide members for moving said bearings relative thereto.

3. A power unit as claimed in claim 2 and further characterized in that said base frame includes a pair of spaced substantially parallel longitudinally extending side skid members each having upwardly curved bottom end surfaces and an eye adjacent each end thereof, and a drive shaft is connected with each engine and journaled in bearings secured to a pair of said cross-frame members to drive a power take-off shaft, and means are provided for vertically adjusting said power take-off shaft relative to said drive shaft and include a pair of vertically adjustable slideable bearings and slides mounted between vertically spaced cross-frame members of said base frame and said motor supporting frame, and means for adjustably sliding said bearings in said slide members.

4. A power unit including a plurality of separate internal combustion engines interconnected for unitary operation to supply power to a single power take-off shaft and having a rigid frame, including a base frame, and a vertically spaced motor supporting frame secured to said base frame, including spaced substantially parallel side frames interconnected by a plurality of cross-frame members, and a centrally disposed longitudinally extending member positioned between said side frames and extending between a pair of said cross-frame members adjacent one end of said motor supporting frame to provide with said side frames a plurality of rigid engine frame cradles, each of said engines being connected with a drive shaft journaled in bearings secured to a pair of said cross-frame members to drive said power take-off shaft, said power take-off shaft being journaled in a pair of vertically adjustable bearings, one adjacent each end of said power take-off shaft, and moveable in a pair of spaced slide members, said slides being secured between vertically spaced cross-frame members of said base frame and said motor supporting frame, and means for adjustably moving said bearings in said slide members.

RAY F. THORNTON.
